CAM ACTION MAGAZINE TYPE TACK HAMMER

Eugene G. Schick, Fort Worth, Tex., assignor to
Tok, Inc., Amarillo, Tex., a corporation of
Texas

Application October 5, 1950, Serial No. 188,555

3 Claims. (Cl. 1-45)

1

This invention relates to a magazine type tack hammer and has reference to improvements in feeding mechanisms therefor for moving the tacks into position to be driven.

An object of the invention is to provide a magazine type tack hammer having a relatively slow cam action for moving and positioning the tacks therein, and whereby the tack feeding mechanism is not subjected to damaging impact or shock loads.

Another object of the invention is to provide a reciprocating tack moving ratchet in a hammer of the described class wherein a partial stroke of the ratchet will not move the tacks in to the discharge end of the magazine.

A further object of the invention is to provide a magazine construction for a tack hammer wherein the position of tacks in the magazine may be readily determined at any time.

The invention will be more readily understood by reference to the accompanying drawings and the following description.

Figure 1 is a side elevation and broken sectional view showing a magazine type tack hammer embodying the features of the present invention.

Figure 2 is an enlarged broken vertical sectional view of the forward or head end of the hammer illustrated in Figure 1.

Figure 3 is a sectional view taken on lines 3-3 of Figure 2.

Figure 4 is a broken perspective view of a strip of joined tacks and showing the position of the ratchet relative thereto.

The strip of tacks 10 shown have their heads 11 joined to each other on opposite sides thereof, and have their shanks 12 parallel with each other and pointing in the same direction. Indentations 13 are provided between the respective heads whereby the tack being driven may be sheared from the strip. Within the meaning of the present invention, the strip of tacks 10 do not have to be joined in the manner described, but may be secured in strips by other means, such as by means of strips of paper, as illustrated and described in U. S. Patent No. 1,162,678 issued November 30, 1915, to C. S. Boden.

The present magazine type tack hammer includes a handle 14 and a hand grip 15 on one end thereof. The end of the handle 14 opposite the hand grip 15 is provided with a head member 16 having a solid laterally projecting head 17 integral therewith. The portion of the head member 16 opposite the solid head 17 is provided with an integral lateral projection 18 having an outwardly and forwardly directed cam surface 19 on the side thereof adjacent the handle 14.

The magazine 20 is comprised of spaced parallel sides 21, each having a laterally projecting ear 22 for attachment to the handle 14 near the grip

2

15 by means of a pin 23 passing therethrough. The sides of the magazine 21 are rigidly secured to each other by means of a frame 24 in the form of a bar which is rectangular in cross section. 5 The sides 21 may be secured to the bar 24 by suitable means, such as welding, brazing, riveting or the like. Beneath the frame 24 and spaced therefrom there is a rail 25 secured to the inner face of each side 21 and so arranged as to form 10 a T slot 26 throughout the length of the magazine 20. The ends of the frame 24 and the rails 25 are curved outwardly from each other at the pivoted end of the magazine 20, as at 27 and 28, to provide a convenient means for inserting the strip 15 of tacks 10.

Referring now to the end of the magazine 20 opposite its pivot pin 23, there is an enlargement 29 in each magazine side 21 and outwardly formed to receive one end of an elongated body member 30, and is secured thereto by means of screws 31. An opening 32 is formed through the length of the body 30 and slidably receives a draw bar 33 having an upturned end 34 on the end thereof opposite the cam surface 19. The upturned end 34 projects above the body 30 whereby the draw bar 33 may be manually operated during the loading operation, to be described. A compression spring 35 is positioned against the outer surface of the turned up end 34, and the remaining end of the spring is secured by tabs 36 in the enlarged sides 29 of the magazine sides 21. A dimple 37 (Figure 3) is formed in the upturned end 34 and is received within the adjacent end of the compression spring 35.

The end of the draw bar 33 opposite the upturned end 34 projects through the body 30 and is in sliding contact with the cam surface 19. As will become apparent, the rise of the cam surface 19 is such that it will move the draw bar 33 a distance equal to the width of any one tack head between the indentations 13. The forward end of the frame 24 terminates near the outer end of the body 30 so as to provide a cavity 38 which accommodates a ratchet 39 secured to the lower surface of the draw bar 33. The forward end to the ratchet 39 is substantially in the form of an inverted U in lateral cross section and has a rearwardly and upwardly directed curved spring 41 on its rearward end for attaching the ratchet 39 to the draw bar 33, as by means of a rivet 40. The teeth 42 of the ratchet 39 are formed on both the lower sides and are spaced from each other at distances equal to the widths of the tack heads 11. The teeth 42 are flat across their lower ends and are normally received outwardly of and between the adjacent tack heads 11. As particularly shown in Figure 4, the width of the ratchet 39 is less than the maximum width of the strip of tacks 10 and the

teeth fit between adjacent tack heads 11 when moving the latter forwardly. A holding spring 43 is secured to the bottom of the body 30 by means of a rivet 43a and has its remaining end positioned to contact the upper surfaces of the tack heads 11 as they pass therebeneath. Although not shown, the projecting end of the spring 43 may be forked so as to straddle the tack heads 11 where they join each other so as to prevent the tacks 10 from moving rearwardly during the return movement of the ratchet 39. A cylindrical driver 44 is slidably positioned through a transverse opening 45 in the forward end of the body 30 and through an elongated opening 61 in the draw bar 33. The driver has an enlarged head 46 having a spherical surface 47 on the upper end thereof. A U-shaped spring 48 having outwardly directed flanges 50 in its upper end is slidably received within opposing slots 51 in the hammer head member 16, and which spring includes a relatively large opening, not shown, therethrough, and engages the driver head 46 and positions the spherical surface 47 thereof against the lower central surface 62 of said head member. Opposing holes 52 and 53 are drilled in the head member 16 and the body 30 and receive a compression spring 54 for normally urging said member and said body away from each other.

Head side members 55 are secured to the opposing sides of the body 30, as by welding, and extend upwardly adjacent the sides of the head member 16. There is an arcuate slot 56 in each head side member and which slots are formed on an arc about the center of the magazine pivot pin 23. A pin 57 is positioned through the head member 16 and projects through the slots 56. If desired, washers 63 may be secured on the pin 57 to prevent the head side members 55 from bending outwardly. It is thus apparent that the length of the slot 56 limits the movement of the body 30 relative to the head member 16, and together with the pin 57, provide for movable attachment of one end of the magazine 20 with the head member 16. Beneath the end of the member 30 and positioned adjacent the driver opening 45 therein there is a block or nose member 58 having a cylindrical opening 59 therethrough, together with a slot 60 formed to admit the strip of tacks 10 therethrough, and which slot is a continuation of the first named slot 26. The nose member 58 is welded or otherwise rigidly secured to the body 30, as shown. The nose member 58 is made separately from the body 30 for the purpose of conveniently forming the tack accommodating opening 60, since the body 30 would otherwise be difficult to machine.

In operation, a strip of tacks 10 is inserted in the slot 26, in the magazine 20 at the end thereof adjacent the magazine pivot pin 23. The heads 11 are manually forced past the teeth 42 of the ratchet 39 and into a position in the cylindrical opening 59 of the nose piece 58. The hammer is then held by the hand grip 15 and the nose piece 58 is struck against the surface in which the tack is to be driven. The driver 44 then strikes the tack head 11 and drives the tack in place. At the same time the action of the cam surface 19 on the end of the draw bar 33 moves the latter rearwardly and causes the teeth 42 of the ratchet 39 to be engaged between the adjoining heads of the rearwardly positioned tack heads 11. The holding spring 43 prevents the entire strip of tacks 10 from moving rearwardly at this time. The compression spring 54 be-

tween the head member 16 and the body 30 separates the same and at the same time the compression spring 35 in the magazine 20 moves the draw bar forwardly as the driver 44 permits such action. The forward movement of the draw bar 33 positions another tack within the opening 59 in the nose 58 and the hammer is again ready for driving said tack. If any tack is only partially driven, the action or stroke of the draw bar 33 is incomplete, and by reason of the described shape of the teeth 42 the remaining tacks are not gripped for moving the same forwardly. In the latter event, the position of the head member 16 may be reversed and a single blow of the solid head 17 may be used for completing the driving of the partially driven tack without interfering with the tack moving action.

The present invention is not limited to the construction herein shown and described, but may be made in many ways within the scope of the appended claims.

What is claimed is:

1. In a magazine type tack hammer including a handle and a head member on one end of said handle, the combination of a tack magazine having a tack passage slot through the length thereof, said magazine having one end thereof pivotally secured to said handle and having the remaining end thereof movably secured to said head member, a driver projecting from said head member and slidably positioned through the end of said magazine opposite its said pivoted connection and transversely through said tack passage slot, a cam carried by said head member, a draw bar slidably mounted in said magazine and positioned to engage said cam, and a tack engaging ratchet secured to said draw bar and positioned to engage and move the tacks in said tack passage slot toward said driver.
2. In a magazine and feed mechanism for a tack hammer as defined in claim 1, the construction wherein said ratchet is in the form of an inverted U in transverse cross section, and having flat end teeth along the sides thereof.
3. In a magazine type tack hammer including a handle and a head member on one end of said handle, the combination of a tack magazine having a tack passage slot through the length thereof, said magazine having one end thereof pivotally secured to said handle and having the remaining end thereof movably secured to said head member, a driver pivotally secured at one end thereof to said head member, and having its remaining end slidably positioned through the end of said magazine opposite its said pivoted connection and transversely through said tack passage slot, a cam carried by said head member, a draw bar slidably mounted in said magazine and positioned to engage said cam, a tack engaging ratchet secured to said draw bar and positioned to engage and move the tacks in said tack passage slot toward said driver, spring means carried by said magazine urging said draw bar against said cam, and spring means urging said magazine away from said head member.
